Primary Examiner—Terry A. Wallace*Assistant Examiner*—Sandra Morris*Attorney, Agent, or Firm*—Christier, Parker & Hale[57] **CLAIM**

The ornamental design for sand comb, as shown and described.

DESCRIPTION

FIG. 1 is a front perspective view of a sand comb, showing my new design;

FIG. 2 is a top plan view thereof;

FIG. 3 is a front elevational view, the rear being a mirror image thereof;

FIG. 4 is a bottom plan view thereof;

FIG. 5 is a right side elevational view, the left side being a mirror image thereof;

FIG. 6 is a perspective view of a second embodiment thereof;

FIG. 7 is a top plan view thereof;

FIG. 8 is a front elevational view, the rear being a mirror image thereof;

FIG. 9 is a bottom plan view thereof;

FIG. 10 is a right side elevational view, the left side being a mirror image thereof;

FIG. 11 is a perspective view of a third embodiment thereof;

FIG. 12 is a top plan view thereof;

FIG. 13 is a front elevational view, the rear being a mirror image thereof;

FIG. 14 is a bottom plan view thereof;

FIG. 15 is a right side elevational view, the left side being a mirror image thereof;

FIG. 16 is a perspective view of a fourth embodiment thereof;

FIG. 17 is a top plan view thereof;

FIG. 18 is a front elevational view, the rear being a mirror image thereof;

FIG. 19 is a bottom plan view thereof; and,

FIG. 20 is a right side elevational view, the left side being a mirror image thereof.
